(57) **CLAIM**

The ornamental design for a clamp kit for a towel, as shown and described.

DESCRIPTION

FIG. 1 is a top plan view of a clamp kit for a towel showing my new design;

FIG. 2 is a bottom plan view thereof;

FIG. 3 is a right side elevation view thereof, the opposite side being a mirror image of the shown;

FIG. 4 is a front elevation view thereof; and,

FIG. 5 is a rear elevation view thereof.

The broken lines in FIG. 1 of the drawings form no part of the claimed design.
